of Delaware

Application August 30, 1932, Serial No. 631,000

11 Claims. (Cl. 250—20)

My present invention relates to automatic amplifier gain control circuits, and more particularly to novel and improved automatic volume control arrangements for high frequency amplifiers especially adapted for use in radio receivers.

One of the main objects of my present invention is to provide an automatic volume control arrangement for use in a radio receiver wherein the coupling between the source of signal energy and the radio frequency amplifier of the receiver is controlled automatically by the amplifier output energy in such a manner that a substantially constant carrier level is maintained at the amplifier output.

Another important object of my present invention is to provide in combination with a source of signal energy to be amplified and an amplifier for the energy, a control arrangement which is adapted to maintain the transfer of energy between the source and the amplifier substantially constant, the said energy transfer being varied in an inverse manner with respect to the amplifier output.

Still another important object of the present invention is to provide in combination with an automatic volume control circuit of the type which automatically controls the radio frequency input to a radio frequency amplifier, an automatic gain control circuit which is adapted to control the amplification of the aforementioned amplifier in order to provide a balanced automatic volume control arrangement.

Another object of the present invention is to provide a radio receiver which includes a source of signal energy and a radio frequency amplifier, an automatic volume control arrangement comprising a normally unbalanced bridge arrangement arranged between the signal energy source and the amplifier input, the bridge being electrically associated with the amplifier output in such a manner that the amplifier output is maintained substantially constant regardless of fluctuations of the signal energy carrier, the receiver additionally including an automatic gain control arrangement connected between the amplifier input and its output whereby the amplification of the amplifier is controlled in a predetermined manner as the energy transfer to the amplifier input is controlled.

Still another object of the present invention is to provide a bridge type automatic volume control arrangement for a radio receiver wherein the bridge includes an electron discharge tube as an arm thereof, and the bridge is arranged between

the antenna and radio frequency amplifier of a radio receiver, the amplifier output being utilized to provide energy for controlling the conductivity of the bridge tube whereby the transfer of energy from the antenna to the amplifier may be automatically controlled.

Still other objects of the present invention are to improve generally automatic volume control arrangements, and to particularly provide automatic volume control circuits for radio receivers which are not only durable and reliable in operation, but economically manufactured and assembled in radio receivers.

The novel features which I believe to be characteristic of my invention are set forth in particularity in the appended claims, the invention itself, however, as to both its organization and method of operation will best be understood by reference to the following description taken in connection with the drawings in which I have indicated diagrammatically several circuit organizations whereby my invention may be carried into effect.

In the drawings,

Fig. 1 shows in schematic fashion a radio receiver embodying one embodiment of the invention,

Fig. 2 shows a modified form of the invention,

Fig. 3 shows a modification of the arrangement shown in Fig. 2,

Fig. 4 shows still another modified form of the invention shown in Fig. 2, and

Fig. 5 shows a modification of a control portion of the arrangement shown in Fig. 2.

Referring now to Fig. 1 of the accompanying drawings, which shows schematically a portion of a conventional radio receiver embodying a form of the present invention, it is pointed out that the numeral 1' represents a conventional type of radio frequency amplifier whose output is to be controlled so as to be of a substantially constant level in spite of the fluctuations of the carrier level in the input energy supplied to the said amplifier. The input circuit of the amplifier 1' is shown as of the tunable type, and comprises an inductance coil 2' shunted by a variable tuning condenser 3, the inductance 2' being shown inductively coupled to a pair of inductive arms 4, 5 of a Wheatstone bridge arrangement.

The antenna, or other signal energy collecting means A is connected to one point a of the bridge, while the diagonally opposite point b is grounded. Point c of the bridge, the ungrounded terminal of inductive arm 4, is connected to point a through 55

- a resistive arm 6 of the bridge, the resistor 6 being shunted by a condenser 7.
- The fourth arm of the bridge comprises the plate to cathode capacity 8 (shown in dotted lines) of an electron discharge tube 2, the cathode of tube 2 being connected to the ungrounded end of inductive arm 5, and the plate of tube 2 being connected to the point *a* of the bridge. The plate of tube 2 is maintained at a positive potential through a path which includes the radio frequency choke coil L and source of potential 15. The high potential side of the output circuit of amplifier 1' is connected, through a lead 9 and condenser 14, to the grid of an electron discharge tube 1, while the cathode of tube 1 is connected to the low potential side of the output of amplifier 1'. Tube 1 is biased for plate rectification by means of battery 13 and resistor 12.
- 20 The anode of tube 1 is connected to its cathode through a path which includes a potential source 10 in series with a resistor R₁, the positive terminal of source 10 being connected to the anode of tube 1. The cathode of the bridge tube 2 is connected to the cathode of tube 1. The control electrode of tube 2 is connected, through a path which includes the resistor R, to the junction of resistor R₁ and the negative side of the potential source 10. A condenser C₁ is connected 25 across the control electrode and cathode of tube 2 and a condenser C₂ is connected across the resistor R₁. The grid of tube 2 is biased by means of battery 11 which also overcomes the drop in R₁ due to the steady current in tube 1.
- 30 35 The symbol *e_o* represents the signal input potential impressed across the bridge input circuit of amplifier 1' between antenna point *a* and ground point *b*. The symbol *e_g* represents the output energy potential delivered to the input of the next stage succeeding the amplifier 1'. The next stage may be a detector circuit, or an additional tuned radio frequency amplifier circuit. The purpose of the arrangement shown in Fig. 1 is to maintain *e_g* substantially constant 40 in spite of fluctuations in the level of *e_o*.
- 45 This is accomplished by normally maintaining the antenna bridge circuit, which is coupled to the tunable input circuit of amplifier 1', unbalanced. That is, the constants of the bridge are so chosen that a predetermined degree of unbalance is secured for a desired value of *e_g*. Obviously, when the bridge is unbalanced the signal collecting means A will be capable of delivering signal energy to the amplifier 1'. However, as soon as the carrier potential level increases above that value which will result in the desired value of *e_g*, then the conductivity, or conductance *g_p*, of tube 2 will be varied by the control tube 1 in such a manner that the bridge will approach 55 balance and the input energy delivered to the amplifier 1' be decreased.
- 50 Conversely, if the carrier potential level falls below the desired level, then the control tube 1 will function to vary the conductance of tube 2 in that direction which will still further unbalance the bridge and increase the energy delivered to the input of amplifier 1'. In this way it will be seen that the path between the output of amplifier 1' and the input bridge, which includes 55 tubes 1 and 2, functions to automatically control the transfer of energy from the signal collecting means and the input of the amplifier 1' in such a manner that the value *e_g* is maintained substantially constant. The tube 2 functions as 70 a variable radio frequency conductance which

depends on the direct current potential applied to its grid. This, in turn, depends upon the rectified output of the control, or rectifier, tube 1.

In Fig. 2 is shown a modified form of the invention wherein the bridge-type automatic volume control of Fig. 1 is combined with grid bias type automatic volume control. That is, the signal collecting means A is again connected to the point *a* of the bridge, while the point *b*, at the junction of the inductive arms 4 and 5, is 10 grounded. The tube 2 comprises the fourth arm of the bridge, the cathode of tube 2 being connected to the ungrounded terminal of the inductive arm 5 in this case, while the grid of tube 2 is connected to a point on resistor R₁ through 15 resistor R. The anode of tube 2 is maintained at a positive potential through a path which includes the radio frequency choke coil L, by connecting it to the positive terminal of a source of anode potential B, which source is not shown, 20 direct current blocking condensers being connected between point *a* and the antenna circuit A and between point *a* and the resistor 6.

The anode of rectifier tube 1 is connected by a lead 11 to the low potential side of coil 2', 25 while the rotor of tuning condenser 3 is connected to ground point *b* through a lead 12. The radio frequency by-pass condenser 13 is connected between the lead 12 and the low potential side of inductance 2', and a condenser 14 is connected between the grounded side of condenser 3 and the grid voltage lead to tube 2, a condenser 15 also being connected in shunt with the grid and cathode of tube 2.

A lead 16' connects the point of zero potential 35 of resistor R₁ to the cathode of the amplifier 1' through a bias potential source 20. The input electrodes of rectifier tube 1 are connected across the output circuit of amplifier 1', the grid of tube 1 being connected through a condenser 16 to the 40 high potential side of amplifier 1', while the cathode of tube 1 is connected through potential sources 17 and 18 to the low potential side of amplifier 1'. A resistor R₂ is connected from the grid of tube 1 to the negative side of potential 45 source 17, while a lead 19 is connected between the low potential side of resistor R₁ and the low potential side of amplifier 1'.

In considering the operation of the arrangement shown in Fig. 2 it will be seen that the transfer of signal energy to the tunable input circuit of amplifier 1' is controlled by the state of balance of the Wheatstone bridge arrangement, and that the amplification, or gain, of the amplifier 1' is additionally controlled. In other words, 55 the rectified output of rectifier tube 1 not only controls the conductance of bridge tube 2 so as to vary the state of balance of the antenna bridge, but also controls automatically the bias of the grid of amplifier 1'.

Thus, when the output of amplifier 1' increases above the desired value of *e_g*, the potential drop across resistor R₁ increases, with the result that the anode side of resistor R₁ becomes more negative thereby increasing the negative bias on the 65 grid of amplifier 1'. This results in a decrease in the amplification of amplifier 1'. At the same time, the conductance of tube 2 is varied in a direction such that the antenna bridge will approach a balance condition, thus reducing the 70 transfer of energy to the amplifier 1'. Should the signal energy level *e_o* decrease below that value which is desired, then the reverse action occurs with the result that the value of *e_g* is maintained substantially uniform.

While the operation of both types of automatic volume control have been explained as simultaneous, it is to be clearly understood that the circuits may be arranged so that the control action on the grid of amplifier 1' does not commence until after the control action on tube 1 has progressed to a considerable extent, and from that point on these two control actions may continue simultaneously. Again, it is quite evident that the two control actions may be successive, one not beginning until the other has ended.

In any event, the essential feature of the present composite, or balanced, automatic volume control system results in a type of automatic volume control action wherein the antenna bridge may not, after approaching a state of balance, be thrown into a state of unbalance again, by a continued increase of the value of e_g .

As shown at present the two control systems (bias control in amplifier and bridge balance) may operate simultaneously, or may be made to operate at different rates. By properly selecting anode and bias voltages, and setting the taps on R_1 the bridge may be made to approach balance slowly while the amplifier gain may change rapidly as the control bias increases, or again the bridge may be made to approach balance rapidly and remain approximately balanced for increasing negative grid bias while the amplifier gain is reduced continually as the control bias increases. The control action is more or less overlapping of course.

In Fig. 3 is shown a modified form of composite automatic volume control arrangement of the type shown in Fig. 2. The amplifier to be controlled comprises a 224 screen grid tube having its control electrode connected to the high potential side of the amplifier input circuit 2', 3 through a condenser 20 having a magnitude of the order of 100 micro micro-farads. The cathode of tube 1' is connected to the low potential side of the resonant circuit through a bias resistor 21. It should be noted that the low potential side of the circuit 2', 3 is grounded, and connected through a fixed condenser 22 to the point b at the junction of the inductive bridge arms 4, 5. The point b of the bridge is shown arranged for connection to ground (0 volts), or, if desired, to a source of voltage 38. The antenna A is connected to point a , while a variable condenser 23, resistor 36 and direct current blocking condenser 37 comprise one arm of the bridge, coils 4 and 5 comprise the second and third inductive arms, the fourth arm of the bridge comprising the bridge tube 2, also designated in Fig. 3 by the letter X.

The anode of the balancing tube 2 has positive potential applied to it from a source B (not shown) through a path which includes a choke coil 24, one end of the choke coil being connected to point a while the other end is grounded through a condenser 25. The plate to cathode capacity of tube 2 is shown in dotted lines, and is designated by the numeral 8. The grid of tube 2 is connected by a lead 26 to a movable arm 27 arranged to contact either of the pair of terminals 28, 29.

The terminal 28 is connected through a lead 30 to the high potential side of resistor 21, the resistor 21 being shunted to ground by a by-pass condenser 31. The terminal 29 is connected to lead 32 which is connected between the normal automatic volume control tube (not shown) and the negative side of the automatic volume control biasing resistor R_1 . The lead 33 and resistor

34 provide the normal automatic volume control bias path between the grid of amplifier tube 1' and the negative end of the bias resistor R_1 . The low potential side of the leak resistor 34 is by-passed by an appropriate condenser 35.

The anode of amplifier tube 1' is adapted to be connected to the grid of the succeeding amplifier stage, and the normal automatic volume control tube not shown in Fig. 3 is to be understood as comprising, if desired, the rectifier tube 1 shown in Fig. 2. The rectifier tube 1 may employ for its input the output of amplifier tube 1', or the output of a succeeding amplifier stage, or even the output of the receiver detector stage, in which case the automatic volume control tube functions as a direct current amplifier.

The operation of the arrangement shown in Fig. 3 corresponds to that explained in connection with Fig. 2. When the arm 27 is connected to terminal 29 then the output of the normal automatic volume control tube controls the direct current potential of the grid of the bridge tube X, and also the grid potential of the amplifier tube 1'. However, when the arm 27 is connected to terminal 28, then the balancing bridge tube X has its grid potential derived from the positive side of the resistor 21 in the circuit of amplifier 1'.

In this case the grid potential applied to the balancing tube X may be operated at a positive voltage even though a relatively high current (compared to the current through R_1) flows in the grid circuit of tube X. In this case tube 1' may be said to operate as a direct current amplifier between the voltage source R_1 and tube X, while it is also operating as the normal signal amplifier.

The reason for obtaining bias for tube 2 from resistance 21 rather than from R_1 when the grid bias of tube 2 is positive is that appreciable grid current flows in tube 2 and this current is small compared to current in 21, but large compared to current in R_1 . It would be impractical to operate tube 2 directly from R_1 when the grid bias of tube 2 is positive. The tube 1' may be considered as a direct current amplifier in that the direct current voltage across the relatively high resistance R_1 is converted by tube 1' to a direct current voltage across the relatively low resistance 21 while at the same time tube 1' is also being used as a radio frequency amplifier.

Another modified form of composite automatic volume control arrangement is shown in Fig. 4; there is utilized in place of a Wheatstone bridge arrangement between the signal energy source and the controlled amplifier, an arrangement as shown in Fig. 4. In this figure the receiver is shown as comprising the usual grounded antenna circuit A which is inductively coupled, as at M_1 , to the tunable input circuit of amplifier tube 40 which is of the screen grid type. The plate of tube 40 is arranged for inductive coupling to the tunable input circuit of the succeeding screen grid amplifier 41 through a coil 42. One end of the coil 42 is connected to the positive terminal 65 of the anode potential source B_1 , it being noted that the negative terminal of this source is connected to the grounded cathode lead of tube 40.

The grid circuit of tube 40 includes a negative biasing potential source C_1' , and the variable tuning condensers 43 and 44 arranged respectively in the input circuits of tubes 40 and 41 are disposed for mechanical uni-control as shown by the dotted lines 45. The coil 42 is coupled to the coil 42' of the tunable input circuit of the tube 41. 75

A third inductance coil 45 connected at one terminal thereof to the positive side of source B₁, and its other terminal by means of a lead 46 to the plate of a screen grid balancing tube 40', 5 is also coupled to coil 42', but in a reversed direction.

It will, therefore, be seen that the anode circuits of tubes 40 and 40' are inductively coupled to the tunable input circuit of tube 41, and that 10 the control grid of tube 40' is connected to the grid circuit of tube 40, and to the high potential side of tuning condenser 43, through a path which includes the condenser 47. The cathode of tube 40' is connected to the ground point of the cathode of tube 40.

It will now be seen that signal energy applied to the tunable input circuit of tube 40 is similarly applied through the radio frequency condenser 47 to the control grid of balancing amplifier tube 20 40'. The outputs of tubes 40 and 40' are simultaneously impressed in opposite directions, across the tunable input circuit of amplifier tube 41 so that when the amplification of tubes 40 and 40' are equal, signal voltages of equal amplitude, but 25 opposite phase, are set up in coil 42' and the combined signal output from the tubes 40 and 40' in the circuit 42', 44 is zero.

The application of output energy from amplifier tube 40' upon the tunable input circuit of tube 30 41 may be controlled by means of a rectifier tube 48 which has its control grid connected to the anode circuit of tube 41, or to the output of succeeding amplifier stages, through a radio frequency condenser 49, the cathode of tube 48 being 35 connected to the low potential side of tube 41 through a path which includes the source B₂, the resistor 50, and the lead 51. A resistor 52 is connected between the anode of tube 48 and the resistor 50, and the positive terminal of source 40 B₂ is connected to one side of resistor 50, while the negative terminal of source B₂ is connected to the cathode of tube 48.

The cathode of tube 48 is connected to the control grid of tube 48 through a path which includes 45 biasing potential source C₂ and a resistor 53 connected in series between the said control grid and the negative terminal of the source C₂. The anode of tube 48 is connected to the control electrode of the amplifier tube 41 through the leak resistor 56, while the control grid of balancing tube 40' is connected to a point E_{co} of the source B₂ through the resistor 55.

The operation of the arrangement shown in Fig. 4 may be explained in the following manner: 55 When the signal energy level in the output of tube 41 increases above the desired level, the output of rectifier tube 48 increases with the result that the negative potential applied through lead 54 to the grid of tube 41 increases, while the positive control potential applied to the grid of balancing tube 40' through resistor 55 increases. This results in a greater flow of current through the coil 45, and consequently results in a decrease in energy transfer from the output circuit 60 of amplifier 40 to the input circuit of controlled amplifier 41. Simultaneously, of course, the amplification of tube 41 has decreased and as explained heretofore, the two control actions may be successive, or overlapping, in relationship. 65 Should the energy output of tube 41 decrease below the desired level, then the reverse action would take place, and the energy delivered to the tunable input circuit of tube 41 would be increased, while the amplification of tube 41 is 70 75 increased.

The outputs of tubes 40 and 40' are coupled to the input circuit of tube 41 in reversed directions so when the outputs from 40 and 40' are equal they balance, and no input signal is transferred to tube 41. When the amplification of either 40 5 or 40' is changed the outputs no longer balance and a signal is passed on to tube 41, the magnitude of which depends on the degree of unbalance. Normally, (as shown in Fig. 4) with no input signal in A, tube 40 is biased for a high amplification (low bias), and tube 40' is biased for low amplification (high bias). When signal at A increases to such a value that the output from 41 10 (or succeeding stages) operates automatic volume control tube 48, the bias of tube 40' is made 15 lower (more positive) by the voltage across 50, and the output signal from 40' increases in opposition to the output from 40, thereby lowering the combined output from 40 and 40'.

This continues with increasing input at A until 20 the amplification of 40' equals that of 40, when the outputs balance out, and the combined output is zero. This operation may be reversed by biasing tube 40 for low amplification (high bias) and tube 40' for high amplification (low bias). Then, 25 to approach balance in the combined outputs of 40 and 40', as the signal input at A increases, the bias of 40' would be increased (negatively) which both lowers the amplification of 40' and approaches a balance in the combined outputs. 30

Normal amplification reduction in amplifier 41 occurs at the same time, of course, by the increasing negative bias supplied by 52. The balancing system will operate, then, when the amplification of either of the pair of tubes 40 and 40' change 35 relatively, which may be accomplished by (1) maintaining one constant and changing the other, (2) changing both in opposite directions, and (3) changing both in the same directions, but at 40 different rates.

If desired, instead of controlling the lower tube 40', the upper tube 40 may be controlled, and both tubes 40 and 40' may even be controlled by the rectified output of tube 48. If the upper tube 40 is controlled by the rectified output 45 of tube 48, then all biases can move negatively together; that is to say, the bias applied to the control grid of tube 40 and then applied to the control grid of tube 41 could both be in a negative direction, instead of being positive and negative respectively as shown in Fig. 4. Again, and as pointed out heretofore, the control voltage may be derived from the detector of the receiver, and the tube 48 may then function as a direct current amplifier, the direct current output in that case 55 functioning as shown in Fig. 4 to control the biases of tubes 40' and tube 41.

In each of Figs. 1 to 4 inclusive there is shown various means for obtaining the control bias voltage, and it is to be noted that in each of Figs. 1, 2 60 and 4 the bias is derived from a special rectifier tube. It has already been explained that instead of a rectifier tube, a direct current amplifier working out of the receiver detector may be employed for supplying the control bias voltages. 65 Obviously, there are other methods of obtaining the control bias voltages. For example, a direct current amplifier may be employed in connection with the rectifier tube 48 of Fig. 4, and the direct current amplifier output used to provide the control biases. Additionally, instead of employing an auxiliary direct current amplifier tube, one of the radio frequency amplifier tubes of the receiver may be utilized to simultaneously function as the direct current amplifier tube following the auto- 70 75

matic volume control rectifier. Again, and as shown in connection with amplifier 1' in Fig. 3, the control biases may be derived from a resistor arranged in the cathode lead of the detector.

5 In Fig. 5 there is illustrated an arrangement whereby the control bias for the balancing tube 2 of Fig. 3, for example, may be derived from a resistor 60 arranged in the negative leg of the cathode of the detector, while the negative control bias for the controlled radio frequency amplifier is derived from the potential drop across the resistor 61 arranged in the anode circuit of the usual automatic volume control rectifier 62. The voltage supply of cathode, control grid and 10 anode of rectifier tube 62 is derived from across the B supply potentiometer 63, and the input energy for the rectifier 62 is derived from the source of energy connected to the input electrodes of the detector tube. The negative control bias 15 derived from the drop across resistor 61 is utilized, as pointed out heretofore, for controlling the bias of the radio frequency amplifier.

Instead of using a triode as a control rectifier, it is also possible to use a tetrode, in which case 20 the control grid of the balancing tube 2 would be connected to the control grid of the tetrode, and the potential drop across the biasing resistor in the tetrode anode circuit would supply the negative control bias for the amplifier grid, the 25 auxiliary grid adjacent the anode being utilized in this case to have signal energy impressed thereon from the controlled amplifier output circuit.

While I have indicated and described several 30 systems for carrying my invention into effect, it will be apparent to one skilled in the art that my invention is by no means limited to the particular organizations shown and described, but that many modifications may be made without departing 35 from the scope of my invention as set forth in the appended claims.

What I claim is:

1. In combination with an amplifier, and a source of signal energy, a normally unbalanced 40 bridge circuit arrangement arranged between the source and the amplifier input, and means including a signal rectifier connected between an arm of said bridge and the output of the amplifier for controlling the bridge balance thereby to automatically adjust transfer of energy from said source to said amplifier.

2. In combination with an amplifier, and a source of signal energy, a normally unbalanced bridge circuit arrangement arranged between the 50 source and the amplifier input, and means including a signal rectifier connected between an arm of said bridge and the output of the amplifier for controlling the bridge balance thereby to automatically adjust transfer of energy from said source to said amplifier, said bridge arm comprising an electron discharge tube.

3. In combination with an amplifier, and a source of signal energy, a normally unbalanced bridge circuit arrangement arranged between the 55 source and the amplifier input, and means connected between an arm of said bridge and the output of the amplifier for controlling the bridge balance thereby to automatically adjust transfer of energy from said source to said amplifier said bridge arm comprising a variable radio frequency conductance, and said means comprising a rectifier tube connected between said conductance and the output circuit of the amplifier.

4. In combination with an amplifier, and a 60 source of signal energy, a normally unbalanced

bridge circuit arrangement arranged between the source and the amplifier input, and means connected between an arm of said bridge and the output of the amplifier for controlling the bridge balance thereby to automatically adjust transfer of energy from said source to said amplifier, and additional means connected between said control means and amplifier input circuit for controlling the amplification of the amplifier.

5. In combination, in a radio receiver, a source 10 of signal energy, an amplifier, a normally unbalanced bridge connected between the antenna and the amplifier input circuit, said bridge including an electron discharge tube as an arm thereof, a rectifier connected to the output circuit of said amplifier, and means for connecting the output circuit of the rectifier to the bridge tube and the amplifier in such a manner that the transfer of signal energy to the amplifier, and the amplification thereof, are controlled in accordance with variations in the amplifier output circuit.

6. In combination, in a balanced automatic volume control arrangement for a radio frequency amplifier, a source of signal energy, a 25 bridge including an electron discharge tube as an arm thereof arranged between said source and said amplifier, means for controlling the bias of the amplifier grid, and an automatic volume control tube connected between said bridge tube, 30 biasing control means, and the amplifier output circuit.

7. In combination, in a radio receiver, a radio frequency amplifier, a preceding radio frequency amplifier coupled to said first amplifier, a control 35 tube having its input circuit connected to the input circuit of said preceding amplifier, and its output circuit coupled to said preceding amplifier output circuit and first mentioned amplifier input circuit, and a control rectifier connected between the first mentioned amplifier output circuit, the grid of said control tube, and grid of said first mentioned amplifier.

8. In combination with a radio frequency signal amplifier, a control tube arranged to regulate 45 the transfer of signal energy to the input circuit of the amplifier, a detector tube having its input circuit coupled to the amplifier, an impedance in the detector space current path for developing a direct current voltage whose magnitude depends 50 on the received signal amplitude, means for varying the gain of said control tube with said voltage thereby to relate said transfer regulation to said signal amplitude, a signal rectifier arranged to produce a uni-directional voltage from received 55 signals, said last voltage varying in magnitude with changes in signal amplitude, and means for applying said last voltage to a gain control electrode of said signal amplifier for varying the gain thereof.

9. In combination with a source of signal modulated carrier energy and a following amplifier of said energy, said amplifier being provided with an input circuit resonant to the frequency of said carrier, a transmission network coupled between 65 said source and resonant input circuit, said network including at least one space discharge device, a rectifier network connected to the output circuit of said amplifier, a control connection between the rectifier network and a gain control 70 electrode of the said amplifier for varying the amplifier gain in response to the rectified current variations, and a control connection between the rectifier network and said device for varying the conductivity of said device in response to fluctua- 75

tions in the intensity level of said carrier energy, said transmission network including additional elements so related to said device that the carrier energy transmission therethrough decreases when the conductivity of said device increases.

10. The method of controlling the output energy of a vacuum tube amplifier which comprises simultaneously varying the bias potential applied to the input circuit of the tube and the amount of

input signal supplied thereto in response to variations in the amplitude of said input signal.

11. The method of controlling the output energy of a vacuum tube amplifier which comprises controlling the gain of the tube and the amount of input signal supplied thereto in response to variations in the amplitude of said input signal. 5

STUART BALLANTINE.
